UNITED STATES PATENT OFFICE.

JOSEPH A. BELAIR AND RUSSELL M. SCOTT, OF MONTREAL, QUEBEC, CANADA; SAID SCOTT ASSIGNOR TO JOHN DARCY, OF MONTREAL, CANADA.

OIL BURNER.

Application filed October 18, 1922. Serial No. 595,332.

To all whom it may concern:

Be it known that we, JOSEPH A. BELAIR and RUSSELL M. SCOTT, both subjects of the King of Great Britain, and both residents 5 of the city of Montreal, in the Province of Quebec and Dominion of Canada, have invented certain new and useful Improvements in Oil Burners, of which the following is a full, clear, and exact description.

10 This invention relates to improvements in oil burners, particularly designed for installation in heating apparatus such as domestic furnaces, and the object of the invention is to provide a simple, durable and inexpensive 15 burner which may be easily installed in existing heating apparatus.

A further object is to provide a burner which will be economical and efficient in operation enabling complete combustion of the 20 fuel.

A still further object is to provide a burner capable of consuming almost any of the heavier grades of fuel oil as well as crude oil and residuum.

25 Another object is to provide a burner which when once in operation will burn even the heaviest liquid hydrocarbon fuels with a clean, smokeless flame.

Still another object is to provide a burner 30 which will not be injured or destroyed by the heat of the flame.

The device comprises generally a water-cooled deflecting plate or baffle adapted to be located in the fire box of a furnace, and 35 having a central air passage to the upper end of which an air supply flue is connected. Below the air passage is a combustion cup upon which the fuel burns and between the lower end of the passage and the combustion 40 cup a mixing plate is provided having a central aperture through which liquid fuel may drop into the combustion cup. The combustion cup is mounted above an overflow receiving pan having suitable drainage 45 means.

In the drawings which illustrate one embodiment of the invention:—

Fig. 1 is a front elevation of a furnace partly in section and illustrating the oil burner in section disposed therein.

Fig. 2 is a side elevation of a furnace partly in section to disclose the oil burner therein in elevation.

Fig. 3 is a plan view of the mixing plate.

Fig. 4 is a plan view of the overflow pan.

Referring more particularly to the drawings, 11 designates a furnace of any suitable type, for example, a domestic hot water furnace as illustrated, having a fire box 12 provided in its lower part with grate supports 13 and in its upper part with a doorway 14. The usual ash pit 15 is located below the furnace.

The oil burner forming the subject of the present invention comprises a hollow annular body 16 adapted for connection at its lower part with any suitable number of pipes 17 designed to connect to the return header of the furnace 11. The upper part of the body is adapted for connection to pipes 18 designed to connect with the discharge header of the furnace. In this way the hollow body 16 will be maintained full of water and thereby safeguarded against burning out. Where the burner is installed in a furnace other than of the hot water type connection may be established between the body 16 and any suitable reservoir. The body is disposed in the furnace 12 a short distance below the doorway 14. An air conduit or flue 19 leads from the doorway in a downward direction and connects with the upper end of the opening 20 of the annulus. Preferably any space in the doorway around the flue 19 is closed by a plate 21. The body 16 may be supported in any suitable way, either by the pipes 17 and 18 or otherwise. A fuel supply pipe 22 having a control valve 23 therein extends into the flue 19 and is downwardly turned at its extremity 24, the extremity being preferably located concentric with the opening 20 of the annular body.

A plate 25 rests on the grate supports 13 and is provided, preferably close to its centre, with a plurality of apertures 26 for the admission of air from the ash pit 15.

An overflow pan 27 is mounted on the plate 25 so as to substantially overlie the apertures 26. This pan may be held in place by any suitable means, such as an overflow pipe 28. The pan may be of any suitable shape but is preferably dished as shown, so as to present a convex lower surface which will impart lateral direction to air entering the furnace through the apertures 26. The pan is provided with any suitable means to support a combustion cup, for example, a spider-work of ribs 29. If the supports 29 are of a nature to divide the pan

into sections connecting passages 30 are provided leading from each section to the drain pipe 28. The combustion cup, designated 31, is preferably a dished member sufficient-
5 ly flattened in the centre of its convex sur-
face to rest securely on the support 29. The
material of this cup should be sufficiently
thin to permit of the cup being quickly
10 heated to a temperature which will gasify
or vaporize liquid fuel placed therein. The
combustion cup is preferably not connected
to its support but merely rests securely
thereon so that it may be readily removed
15 for cleaning if such becomes necessary.
The combustion cup is disposed concentrically
of the overflow pan and is of slightly
smaller diameter, as clearly shown, so that
20 an overflow of fuel from any part of the
circumference will drop into the pan. The
cup and pan are disposed a suitable distance
below the body 16 and axially in line with
the central opening 20 thereof.

An air mixing plate 32 is disposed be-
25 tween the combustion cup and the lower end
of the passage 20. This mixer is preferably
a dished plate disposed convex side down
and provided with a plurality of openings
33, through which air may pass, and with
30 a central opening 34 through which fuel
may drop from the pipe 24 into the cup
31. The deflecting plate may be supported
in any suitable way. One convenient method
35 of support is to provide arms 35 on the edges
of the plate adapted to project upwardly
through the opening 20. The upper ends
30 of these arms may be provided with out-
wardly turned fingers 36 adapted to rest
on the upper surface of the body to support
the plate. Preferably the plate is of such
40 a size that it may be withdrawn upwardly
through the opening 20.

The operation of the device is as fol-
lows;—A small amount of fuel is admitted
45 through the valve 23 and drops into the
cup 31 where it is ignited for the purpose
of heating the plate. When the plate is
sufficiently heated to gasify or vaporize the
fuel, the valve 23 is adjusted to admit the
50 desired amount of fuel either as a steady
stream or in drops. The fuel drops through
the opening 20 of the body and through the
opening 34 of the mixing plate and into
the cup 31 where it burns. The flame arising
55 from the cup is deflected radially by
the plate 32 and thus bathes the lower sur-
face of the body. The plate forms a bar-
rier preventing flame rising through the
opening 20, the plate apertures being too
60 small to give passage to the flame. The
natural draught of the heating apparatus
draws air in through the flue 19, which air
is directed downwardly by the flue and pas-
65 sage 20 and then laterally by the plate 32
so as to mingle with the flame bathing the
lower surface of the body. A certain amount

of air flows through the openings 33 and
34 of the plate and mixes with the flame.
In addition, the natural draught draws air
up through the openings 26 to mingle with
the flame. It will thus be seen that air is
70 delivered above the flame and below the
flame and also through the apertures 33 into
the very centre of the flame. An adequate
supply of oxygen and a very complete mix-
ing of the same with the flame is thus ob-
75 tained so that a very efficient combustion
results. The laterally directed streams of
flame and air strike the walls of the furnace
and are thereby further intermingled. Any
80 supply of oil in excess of what will burn
in the cup overflows into the pan 27 and
drains away through the pipe 28. By this
arrangement of air supply it is found possi-
85 ble to dispense with blowers and all man-
ner of fuel atomizing or other pressure de-
vices and to obtain a hot, smokeless flame
and very efficient combustion. The bulk of
90 the combustion takes place below the body
16 but a certain amount occurs above the
body and serves to heat the flue 19 so that
the inflowing air is heated and does not
95 chill the flame. The burner is practically
noiseless in operation and thereby overcomes
one of the great disadvantages of liquid fuel
burning apparatus for domestic purposes.
100 The flame heats the body 16 so that the
water therein is heated and rises through
the pipes 18 directly into the circulatory
system of a hot water furnace, being re-
placed by water drawn through the pipes
105 17 directly from the circulatory system. By
this means the large body of water in the
boiler 11 is short-circuited for a short time
after the burner is in operation. The effect
110 of this is the early establishment of a sup-
ply of hot water in the circulatory system
which renders the device particularly serv-
iceable in the spring and autumn months
115 or in mild climates where only a little heat
is required. After the burner has been in
operation for a while and the main body
of water in the boiler becomes heated it will
120 enter into the circulation. The device is
very simple, durable and inexpensive in con-
struction and may be easily applied to exist-
ing furnaces. The body 16 constitutes in
reality a baffle to deflect the flame and assist
125 in thorough mixing of gas and air. With-
out cooling this baffle would, in a short time,
be burned out but when cooled by establish-
ment of a water circulation therethrough the
device becomes practically indestructible and
has the additional advantage of supplying
comparatively large amounts of hot water
very rapidly.

Having thus described our invention, what
we claim is:—

1. In a device of the class described, an
annular hollow deflecting member, an air
130 flue leading to the upper end of the open-

ing thereof and connected to the member in a manner to exclude furnace gases, a combustion cup disposed below the deflecting member and means for dropping liquid fuel 5 through the opening of the deflecting member into the cup.

2. In combination with a furnace, a plate substantially closing the lower part of said furnace, said plate being apertured around 10 a solid central portion, an overflow pan supported on the central portion of said plate and overlying the apertures thereof and serving to give lateral direction to air entering through the plate apertures, a combustion cup above the pan, a flame deflecting means above the cup, and means for admitting air in a downwardly directed stream 15 into contact with the flame arising from the cup.

20 3. In a device of the class described, a combustion cup, means located thereabove to give lateral direction to flame arising from the cup, means to supply air above and below the flame, and means to give lateral 25 direction to the air above and below the combustion cup.

4. A device of the class described, a combustion cup, means to give lateral direction to flame arising from the cup, means to 30 supply air above and below the cup, means to give lateral direction to such air supply, said last mentioned means including a plate above and separate from the cup and apertured to admit air to the centre of the flame.

25 5. In combination with a furnace having a doorway, a plate substantially closing the bottom of the furnace and having apertures adjacent its centre, means to give lateral direction to air entering through said apertures, a combustion cup, an annular flame deflecting means located above the cup and below the doorway adapted to direct flame 40 against the wall of the furnace, and an air flue leading from the furnace doorway to the opening of said deflecting means and formed to supply air in a downward direction to the flame arising from said cup.

6. In a device of the class described, a 45 combustion cup, a flame deflecting means thereabove apertured above the cup, and an apertured plate interposed between the cup and deflecting means to exclude flame from the aperture thereof, and means to discharge liquid fuel to pass unconfined through the 55 apertures of the deflecting means and plate to the cup.

7. In a device of the class described, a

combustion cup, a fuel conduit terminating above the combustion cup, and a flame deflecting means interposed between the cup 60 and the end of said conduit to exclude flame from the conduit, said means being provided with an aperture sufficiently large for the passage of unconfined fuel and too small for the passage of flame.

65 8. In a device of the class described, a combustion cup, means to supply fuel to the cup, means to admit air beneath the cup, means to admit air above the cup, air deflecting means above and beneath the cup 70 and separate therefrom, the upper deflecting means serving also as a flame deflecting means and being apertured for admission of air to the centre of a flame, and additional flame deflecting means above said upper deflecting member.

9. In a device of the class described in combination with a furnace having a doorway, a plate substantially closing the bottom of the furnace and having a central air 80 inlet, a combustion cup disposed above the air inlet, a drip cup disposed between the combustion cup and air inlet and serving to direct air from the inlet laterally of the combustion cup, a hollow annular flame deflecting means above the cup, a fuel conduit terminating above the cup, a deflecting plate interposed between the end of the fuel conduit and the cup having an opening for 85 passage of unconfined fuel, which opening is too small for the passage of flame, said 90 plate serving also to exclude flame from the central opening of the annular deflecting means, an air conduit leading from the furnace doorway to the central opening of said 95 annulus, and means for circulating water through said hollow annular deflecting means.

10. In a device of the class described, a combustion cup, a deflecting means above the 100 cup having a central aperture for admission of air, a deflecting plate disposed between the deflecting means and cup to deflect and exclude flame from the opening of said means, the said plate being movable through 105 the opening of the deflecting means, and legs on said plate having outwardly turned feet to rest upon the upper surface of the deflecting means and support the plate therebelow.

110 In witness whereof, we have hereunto set our hands.

JOSEPH A. BELAIR.
RUSSELL M. SCOTT.
